United States Patent Office

Des. 222,129
Patented Oct. 5, 1971

222,129

MODULAR BUILDING

Donald V. Baker, Michael D. Reifel, and Lawrence A. Samuelson, Houston, Tex., assignors to Reifel Engineering Company, Houston, Tex.

Filed Nov. 4, 1969, Ser. No. 19,929

Term of patent 14 years

Int. Cl. D25—04

U.S. Cl. D13—1

FIG. 1

FIG. 2

FIG. 3

FIG. 4

FIG. 1 is a front perspective view of a building embodying the design taken in the direction of arrow 1 in FIG. 4;

FIG. 2 is a side perspective view taken in the direction of arrow 2 in FIG. 4;

FIG. 3 is a rear perspective view taken in the direction of arrow 3 in FIG. 4; and

FIG. 4 is a plan view of the building.

We claim:

The ornamental design for a modular building, substantially as shown and described.
